SIGNAL-VALVE-CONTROLLING MECHANISM.

No. 909,717.

Specification of Letters Patent.

Patented Jan. 12, 1909.

Application filed December 29, 1902, Serial No. 136,983. Renewed March 24, 1905. Serial No. 251,848.

To all whom it may concern:

Be it known that we, WALTER V. TURNER and DAVID M. LEWIS, citizens of the United States, and residents of Topeka, Shawnee county, State of Kansas, and Raton, Colfax county, Territory of New Mexico, respectively, have invented certain new and useful Improvements in Signal-Valve-Controlling Mechanism, of which the following is a specification.

Our invention relates to signal controlling valve mechanism, and more especially to such valve mechanism adapted for use in railway trains where a signal train line is supplied with a fluid, such as air, under pressure, and reduced at any point or points in said signal line by the operation of suitably located discharge valves, whereby the pressure is reduced in said signal train line, which reduction of pressure through devices intervening between the signal train line and the signaling device or whistle causes the latter to sound.

Our objects are to provide a valve mechanism of this character which will be the least likely to get out of order, and which will obviate entirely the tendency of the signal valve to repeat or dance, and one whose effective operation will not be interfered with by the usual leaks from any part of the signal system and, at the same time, will be susceptible of being quickly recharged, and, finally, to provide such a valve mechanism as will accomplish these desirable objects in the most efficient and economical manner and will embody the simplest arrangement of parts in the most durable form, capable also of ready application to existing structures wherein the signal train line is connected with some approved type of air brake system, such, for example, as the Westinghouse automatic air brake.

With these objects in view, our invention broadly considered consists in a valve interposed between a source of fluid pressure supply, such as the main reservoir of a fluid pressure railway brake system, normally closed by the pressure in a signal line deriving its fluid pressure from said supply, and opened by a reduction of pressure in said signal line to permit the passage of fluid pressure to the signaling device or whistle; and in a controlling valve mechan-

ism for controlling the supply of fluid to a signaling device or whistle whose operations of opening and closing are dependent upon and controlled by differential reductions of pressure in the signal line and through the signaling device with respect to the reservoir pressure.

Our invention further consists in a valve exposed to pressure on one side to a fluid pressure supply and on the other side to pressure in a signal line deriving its pressure from the fluid pressure supply, with means for permitting a restricted flow of fluid pressure from one to the other, and normally closing the supply of pressure from the source of fluid pressure supply to the whistle or signaling device.

Our invention further consists in the novel construction and details thereof, as herein-after described, with reference to the accompanying drawings, and more particularly pointed out in the claims.

In the drawings, Figure 1, is a top plan view of a structure embodying our invention; and Fig. 2, is a central longitudinal section thereof, on the line 2—2, Fig. 1.

Referring to the drawings, where the same reference characters relate to the same parts in both views, we have shown a convenient and effective form of our invention as embodied in a compact valve structure, in which A is the valve body or casing closed by a chambered screw cap B, in one side of which valve casing is tapped a pipe or conduit C leading from a source of fluid pressure supply, preferably from the main reservoir of an air brake system having the customary reducing valve for maintaining a fixed working pressure in the train line, irrespective of the reservoir pressure. This conduit or pipe opens preferably through a restricted passage e into a chamber N below an abutment or piston I which is carried by a stem L, said piston loosely fitting the valve casing A, and attached to it, or forming a part thereof, is a disk valve F, the beveled face G of which is adapted to close against a correspondingly beveled valve seat H formed on the fixed structure, in the present instance, on the interior of the cap B. The valve G is normally unseated, as shown in Fig. 2, so that any pressure supplied to the chamber N will gradually leak past the loose fitting abutment or piston I

into the chamber O of the cap, and thence through the pipe or conduit E tapped therein and connected to the signal line, thereby maintaining normally the same pressure on both sides of the piston valve. Carried by the stem L is a valve K which normally closes a passage d in the wall of the chamber N leading to a pipe D connected to the signaling device or whistle, and to insure the seating of the said signal controlling valve when pressures are the same on both sides of the piston I, a helical spring M is confined between the said piston and the fixed structure, such spring being shown as having one end seated against the upper face of the valve F, and surrounding a guiding boss thereon, with the other end similarly seated against the cap B and around an inwardly projecting nipple to which the pipe E is attached. A weight may, of course, replace this spring M when the structure is used in a vertical position, or in such position where gravity may act in an equivalent manner to said spring.

In order to keep the valves on the stem L properly centered and to insure easy movement without binding when in operation, we preferably provide the stem with suitable wing guides J, three in the present instance, the outer ends of which bear against the inner surface of the valve casing A, and preferably these guides should be located near the signaling supply controlling valve K, for obvious reasons, to effect the desired object.

While we have described the elements of our invention as assembled in a single valve casing, it is to be understood that the essence of our invention does not require such specific correlation of the parts, although, manifestly, it is preferable to so locate them.

The operation of the device is as follows: With the valve K closing the outlet from the chamber N to the conduit D leading to the signaling device or whistle, it is assumed that air at the pressure fixed by the reducing valve in the connection to the main reservoir, fills the chamber N, and leaking past the loose fitting piston I, such air pressure likewise fills the chamber O and thence through the conduit E, filling the signal line at the same pressure, thereby permitting the spring M to hold the valve F from its seat and keep the valve K closed. When, however, it is desired to sound the whistle, a reduction is made in the signal line, in the usual way, by opening a discharge valve therein, and as the construction of the piston I is such that the air cannot leak through the restricted passage formed by the loose fit of said piston as rapidly as the air is discharged from the signal line, a difference of pressure is immediately established on opposite sides of the piston, and as the higher pressure is on the

side exposed to the air pressure in the chamber N, such excess of pressure immediately causes the piston I to move and with it the valve K, thereby opening a direct communication between the chamber N and, hence, the reservoir, and the signaling device or whistle, thus permitting a sudden rush of air through said whistle and sharply sounding the same, and, at the same time, the valve F is carried by the piston I to closing position. As the pressure in the chamber N is now reduced by the discharge through the fully opened valve K more rapidly than the pressure is supplied from the reservoir, it becomes lower than the pressure in the signal line. When the spring M exerts its force upon the piston I and closes the valve K, air will pass around the piston I and restore the signal line pressure and the parts will resume their normal positions.

It will thus be seen that the principle of the mode of operation of our device resides in the fact that the parts are so constructed that, first, a greater and quicker reduction of air pressure in the signal line is effected at the opening of a discharge valve than can be supplied past the restricted passage around the piston I, and, second, that the reduction past the valve K to the signaling device or whistle is greater and quicker than can be supplied from the reservoir or source of supply to the chamber N, that is to say, there is a differential reduction of pressure in the signal line and in the conduit to the signaling device with respect to the pressure in the chamber N and with respect to each other; therefore, it is evident that the signal valve operates according to changes in pressure at the will of the operator of the discharge valve at any point in the signal line, and it is further obvious that, by the use of our improved signal controlling valve, a quick response at the whistle is assured, while leaks, unless very large, cannot interfere with the effective operation, and quick recharging is secured; furthermore, the objection in former devices for the same purpose, due to "repeating or dancing" is entirely obviated, while the signal device or whistle is caused to give forth a quick, sharp sound, which may be lengthened or shortened, as desired by the operator.

We claim as our invention:

1. In a signaling mechanism operated by fluid pressure, a valve for controlling the flow of fluid to the signaling device or whistle, in combination with a source of fluid pressure supply, a signal line deriving its pressure supply therefrom, a device operatively connected to the valve and controlling the supply of fluid to the signal line, and actuated for opening the signal controlling device by reduction of pressure in the signal line, with means for moving said device to close said valve dependent upon the

greater and quicker reduction of pressure in the passage of fluid to the signaling device than can be supplied from the reservoir, substantially as described.

- 5 2. In a signaling mechanism operated by fluid pressure, the combination of a valve casing connected to a source of fluid pressure supply, a signal line having a connection with said casing, a movable abutment in 10 said casing between the connections to the fluid pressure supply and the signal line, a valve operatively connected to and moving with said abutment for controlling the flow of fluid to a signaling device or whistle, a 15 restricted passage between the fluid pressure supply side and the signal side of said abutment, whereby reduction of pressure in the signal line will cause said abutment to move and open the valve controlling the supply to 20 the signaling device, and means for closing said valve dependent upon the more rapid reduction of pressure to the signaling device than can be supplied from the reservoir, substantially as described.
- 25 3. In a signaling mechanism operated by fluid pressure, the combination with a main reservoir and train pipe of an air brake system, of a valve casing connected thereto, a piston movable in said casing and having 30 one side exposed to pressure from the said reservoir, a signal line communicating with the casing on the other side of said piston, and a valve connected to the piston and controlling the flow of fluid from said casing to 35 the signaling device, and means for closing the said valve when the pressures on the opposite sides of the piston are substantially the same, substantially as described.
4. In a signaling mechanism operated by 40 fluid pressure, the combination of a valve casing, a connection leading therefrom to the main reservoir of an air brake system, a connection between said casing and a signal line, a loosely fitting piston in said casing 45 between said connections, a valve carried thereby for controlling the flow of fluid therefrom to a signaling device, and a spring for moving said piston and closing the valve when pressures on the opposite sides thereof

are substantially the same, said parts being 50 so constructed that reduction in the signal line will be greater and quicker than supplied from the reservoir around the piston and similarly proportioned in the signaling device with respect to the supply from the 55 reservoir, substantially as described.

5. In a fluid pressure signal mechanism, the combination with a signal pipe line, and source of fluid pressure supply for charging said signal line, of a valve device comprising 60 a chamber having a restricted inlet port from said source of supply and a larger outlet signal port, a movable abutment subject to the opposing pressures of said chamber and the signal pipe line, and means operated 65 by said abutment for controlling said signal port.

6. In a fluid pressure signal mechanism, the combination with a signal pipe line, and source of fluid pressure supply for charging 70 said signal line, of a valve device having a signal port and operated by a reduction in signal pipe line pressure for closing communication from said source of supply to the signal pipe line and opening communication 75 from said source of supply through said signal port.

7. In a fluid pressure signal mechanism, the combination with a signal pipe line, and source of fluid pressure supply for charging 80 said signal line, of a valve device comprising a chamber having a restricted inlet port from said source of supply and a larger outlet signal port, a movable abutment subject to the opposing pressures of said chamber 85 and the signal pipe line, and valve means actuated by said abutment under a reduction in signal line pressure to close communication from the source of supply to the signal line and open said outlet signal port. 90

In testimony whereof, we have signed our names to this specification, in the presence of two subscribing witnesses.
